SYNCHRONIZING-SIGNAL SEPARATING APPARATUS

John C. Wilson, Bayside, N. Y., assignor to Hazeltine Corporation, a corporation of Delaware

Application July 13, 1940, Serial No. 345,289

10 Claims. (Cl. 178—7.5)

This invention relates generally to synchronizing apparatus for television receivers.

Various arrangements have been heretofore proposed for the separation of synchronizing signals from a composite received television signal and their use in television receivers. The conventional television signal comprises a vision signal and a composite synchronizing signal including line-synchronizing pulses and a plurality of field-synchronizing pulses during each field-underlap interval of the same polarity as, but of greater duration than, the line-synchronizing pulses. As used in this specification, the term "field-underlap interval" is intended to mean the interval between fields during which no video information is translated by the system. In order accurately to synchronize the field-scanning oscillator, it is necessary to separate the field-synchronizing pulses from the composite synchronizing signal. Certain types of field-synchronizing-signal separating arrangements which have been utilized in prior art television receivers depend upon the integration of the composite synchronizing signal to derive a signal for synchronizing the field-scanning operation of the receiver. This type of synchronizing-signal separator has an advantage in that it is relatively impervious to disturbing noise signals but may have the disadvantage that the timing of the signal derived therefrom is not as accurate as desired.

Another type of field-synchronizing-signal separator which has been used in prior art arrangements depends for its operation upon the differentiation of the field-synchronizing signal to derive a signal responsive to the leading or trailing edges of the pulses of the field-synchronizing signal. This last-mentioned type of synchronizing-signal separator, while providing very accurate timing, may be subject to faulty operation due to noise impulses which may be present with sufficient amplitude and energy content to disturb the operation of the system. Such systems inherently operate on the small amount of energy which can be derived from an edge of the composite synchronizing signal. It is desirable, however, to provide a field-synchronizing-signal separator which contains the desirable attributes of both of the above-mentioned types.

Prior art systems also have been proposed in which the sensitivity of the field-synchronizing-signal separator depends upon an integration of the composite synchronizing signal while the timing of the signal derived from the signal separator depends upon a differentiation of the composite signal, that is, upon energy derived

from an edge of one of the field-synchronizing pulses. However, in such prior art systems also, the derived signal depends only upon the small amount of energy procured from the edge of a synchronizing pulse and, therefore, such systems may be subject to faulty operation due to noise components which are present in the composite signal. It is desirable, therefore, to provide a field-synchronizing-signal separator, the sensitivity of which depends upon an integration or a storing of energy from the composite synchronizing signal and which need not be rendered so sensitive that its operation depends entirely upon the energy derived from an edge of a field-synchronizing pulse. That is, it is desirable to provide a system of the general type under discussion in which a substantial part of the energy of a relatively broad field-synchronizing pulse is available for initiating the scanning operation of the system.

It is an object of the present invention, therefore, to provide an improved field-synchronizing-signal separating apparatus not subject to the above-mentioned disadvantages of prior art arrangements.

It is a further object of the invention to provide an improved field-synchronizing-signal separating apparatus in which a double immunity is provided against interference or noise signals except for a very short time immediately prior to the occurrence of the portion of the signal by which synchronizing is to be effected.

It is still another object of the invention to provide an improved field-synchronizing-signal separating apparatus of the general type under discussion which need not be so sensitive that its operation depends entirely upon the energy derived from an edge of a field-synchronizing pulse.

In accordance with the invention, there is provided in a television signal-translating system a synchronizing-signal separating apparatus adapted to be energized by a composite synchronizing signal including line-synchronizing pulses and a plurality of field-synchronizing pulses for each field-underlap interval of the same polarity as, but having a greater duration than the line-synchronizing pulses comprising means including an integrating circuit responsive to a predetermined one of the field-synchronizing pulses of each field-underlap interval and substantially unresponsive to the line-synchronizing pulses deriving a sensitizing signal initiating at the trailing edge of the above-mentioned predetermined one of the field-synchronizing pulses. Means are further provided responsive to the above-men-

tioned sensitizing signal and to the composite synchronizing signal for deriving a control signal from the field-synchronizing pulse following the above-mentioned trailing edge.

For a better understanding of the invention, together with other and further objects thereof, reference is had to the following description taken in connection with the accompanying drawing, and its scope will be pointed out in the appended claims.

Fig. 1 of the drawing is a circuit diagram, partly schematic, of a complete television receiver of the superheterodyne type embodying a television synchronizing-signal-separating apparatus in accordance with the present invention, while Fig. 2 comprises a series of graphs utilized to explain the operation of the circuit of Fig. 1.

Referring now more particularly to Fig. 1 of the drawing, the system there represented comprises a receiver of the superheterodyne type including an antenna system 10, 11 connected to a radio-frequency amplifier 12, to which are connected in cascade, in the order named, an oscillator-modulator 13, an intermediate-frequency amplifier 14, a vision-signal detector and A. V. C. supply 15, a video-frequency amplifier 16, and an image-reproducing device 17. A line-scanning circuit 18 and a field-scanning circuit 19 are provided, each having an input circuit coupled to the output circuit of detector 15 through a synchronizing-signal separator 20, the field-scanning circuit 19 being coupled to synchronizing-signal separator 20 through a field-synchronizing-signal separator 21 constructed in accordance with the present invention and presently to be described in detail. The output circuits of line-scanning circuit 18 and field-scanning circuit 19 are coupled to the scanning elements of image-reproducing device 17 in a manner well understood in the art. A sound-signal detector and amplifier 22 and a sound-signal reproducing device 23 are coupled to the output circuit of intermediate-frequency amplifier 14. An automatic amplification control potential derived from detector 15 is applied over conductor A. V. C. to one or more of the tubes of radio-frequency amplifier 12, oscillator-modulator 13, and intermediate-frequency amplifier 14 to maintain the amplitude of the signal input to the detector 15 and to the detector stage of unit 22 within relatively narrow limits for a wide range of received signal amplitudes. The stages or units 10-23, inclusive, excepting unit 21 presently to be described in detail, may be of conventional well-known construction so that detailed illustration and description thereof are deemed unnecessary herein.

Referring briefly, however, to the operation of the system described above, television signals intercepted by antenna circuit 10, 11 are selected and amplified in radio-frequency amplifier 12 and translated to the oscillator-modulator 13, wherein they are converted into intermediate-frequency signals which, in turn, are selectively amplified in the intermediate-frequency amplifier 14 and from which the vision-modulated signal is delivered to the detector 15. The vision-modulation components of the signal are derived by the detector 15 and are supplied to the video-frequency amplifier 16, wherein they are amplified and from which they are supplied, in the usual manner, to a brightness-control electrode of the image-reproducing device 17 and to the synchronizing-control elements of scanning circuits 18 and 19 through synchronizing-

signal separator 20. The intensity of the scanning beam of the device 17 is thus modulated or controlled in accordance with the video-frequency voltages impressed upon its control electrode in the usual manner. Scanning waves are generated in the line-scanning and field-scanning circuits 18 and 19, respectively, which are controlled by synchronizing-voltage pulses derived from detector 15, and applied to the scanning elements of the image-reproducing device 17 to produce electric scanning fields to deflect the scanning beam in two directions normal to each other, so as to trace a rectilinear scanning pattern on the screen and thereby reconstruct the transmitted image. Sound-modulated signals derived from intermediate-frequency amplifier 14 are detected and amplified in unit 22 and reproduced in unit 23 in a conventional manner. The A. V. C. potential derived from detector 15 and applied to stages 12, 13, and 14 serves to maintain the signal input to detector 15 and to the detector stage of unit 22 within a relatively narrow amplitude range for a wide range of received signal amplitudes.

Referring now more particularly to the portion of the system embodying the present invention, field-synchronizing-signal separator 21 is adapted to be energized by a composite synchronizing signal including line-synchronizing pulses and a plurality of field-synchronizing pulses for each field-underlap interval of the same polarity as, but having a greater duration than, line-synchronizing pulses and comprises energy-storage means for integrating the composite synchronizing signal, derived from synchronizing-signal separator 20, to derive a first sensitizing signal during each field-underlap interval. This integrating means comprises a resistor 30 connected in series with a parallel-connected resistor 31 and condenser 32, the sensitizing signal derived from the circuit 31, 32 being applied to an outer control grid of a multigrid vacuum-tube repeater 33. The composite synchronizing signal derived from synchronizing-signal separator 20 is also applied to an inner control grid of vacuum tube 33 by means of a coupling condenser 34 and grid-leak resistor 35, vacuum tube 33 being provided with an output circuit including load resistor 36. Suitable unidirectional operating potentials are provided for the several electrodes of vacuum tube 33 by means of unidirectional sources C, C₁, +Sc, and +B, tube 33 being normally biased to cutoff.

The synchronizing-signal separating unit 21 also includes a quickly-responsive and slowly-recovering means including an integrating circuit responsive to a predetermined one of the field-synchronizing pulses of each field-underlap interval and substantially unresponsive to the line-synchronizing pulses and dependent upon the first sensitizing signal derived by the resistance-condenser network 30, 31, 32 for deriving a second sensitizing signal initiating at the trailing edge of the predetermined one of the field-synchronizing pulses. This last-mentioned means comprises an integrating circuit responsive to the field-synchronizing pulses of the composite signal and substantially unresponsive to the line-synchronizing pulses thereof, the circuit including a diode 38 coupled across the load resistor 36 of tube 33 through coupling condensers 39 and 40, a resistor 41 being connected in parallel with condenser 40 through a unidirectional-voltage source C₂. In order to provide means responsive jointly to the sensitizing signal and to the field-synchronizing

pulses of the composite synchronizing signal for deriving a control signal from the field-synchronizing pulse following the above-mentioned trailing edge the second sensitizing signal derived from the resistor-condenser combination 40, 41 is applied to the inner control grid of a second multigrid vacuum-tube repeater 44, while the outer control grid thereof is coupled directly to the load circuit of vacuum tube 33 through coupling condenser 39 and a grid-leak resistor 44', a load circuit including resistor 45 being provided for tube 44. Suitable unidirectional operating potentials are provided for vacuum tube 44 by means of a source C₂, source C₃, and sources +Sc and +B in a manner well understood in the art.

Reference is made to the curves of Fig. 2 for an explanation of the operation of the system of Fig. 1 constituting the present invention. In curve A of Fig. 2, there is illustrated a portion of the composite synchronizing signal derived from synchronizing-signal separator 20 and applied to field-synchronizing-signal separator 21. This composite synchronizing signal comprises a line-synchronizing pulse L and a plurality of field-synchronizing pulses F, F of the same polarity as, but having a greater duration than, the line-synchronizing pulse L. The resistance-condenser network 30, 31, 32 is so proportioned that the voltage developed across condenser 32 rises to a substantially constant level during the first field-synchronizing pulse F of each field-underlap interval as illustrated by curve B of Fig. 2 and a voltage of this wave form is, therefore, applied to the outer control grid of vacuum tube 33; that is, condenser 32 is charged substantially to the maximum voltage represented by the field-synchronizing pulses F during the time interval represented by the first field-synchronizing pulse of each field-underlap interval. Such control grid of vacuum tube 33 is so biased by means of unidirectional source C that the tube is nonconductive in the absence of the sensitizing signal derived from resistance-condenser network 30, 31, 32 but becomes conductive in the presence of such sensitizing pulse, for instance, at an amplitude such as is represented by the dotted line C of Fig. 2. Therefore, it is seen that, at the beginning of each of the field-underlap intervals, tube 33 is nonconductive and is rendered conductive by the sensitizing pulse B derived during the field-underlap interval. Tube 33 is thereafter effective to pass the remaining broad field-synchronizing pulses of the field-underlap interval applied to its inner control grid and is effective to develop an output current and an output voltage across load resistor 36 of the wave form illustrated adjacent the anode of tube 33.

Diode 38 and its associated load circuit comprising condenser 40 and resistor 41 provides a quickly-responsive and slowly-recovering means or an energy-storage device including a short time-constant charging circuit and a long time-constant discharging circuit, the condenser 40 being effectively charged substantially instantaneously upon the occurrence of the first positive step in the output wave of tube 38, which corresponds in time with the trailing edge of the first field-synchronizing pulse F, by virtue of the low internal resistance of diode 38. The time constant of the diode load circuit including condenser 40 and resistor 41 is relatively long so that condenser 40 is not substantially discharged during the succeeding field-synchronizing pulses. There is thus developed across condenser 40 a voltage of the wave form of curve D of Fig. 2 which is applied

to the inner control grid of vacuum tube 44 which, in turn, is so biased by means of source C₂ that it is cut off for control potentials applied to its inner control grid below the amplitude level represented by dotted line E of Fig. 2. The rise of potential across condenser 40, as represented by curve D, therefore, unblocks the inner control grid of tube 44 in time for the second and succeeding field-synchronizing pulses to be passed by tube 44, the resulting voltage G developed across load resistor 45 being utilized to synchronize field-synchronizing circuit 19 accurately on the leading edge of the second field-synchronizing pulse.

It is, therefore, seen that diode 38, condenser 40, and resistor 41 effectively comprises a means which is quickly-responsive and slowly-recovering and which is dependent upon the first sensitizing signal, that is, the signal represented by curve B for deriving a second sensitizing pulse, curve D, initiating at the trailing edge of a predetermined one of the field-synchronizing pulses of each field-underlap interval. Specifically, in the embodiment illustrated, the second sensitizing signal initiates at the trailing edge of the first of the field-synchronizing pulses of each field-underlap interval. Vacuum tube 44 thus comprises a means dependent upon the first and second sensitizing signals for deriving a control signal from the field-synchronizing pulse following the trailing edge of the first field-synchronizing pulse.

It is thus seen that, in the embodiment disclosed, the field-synchronizing-signal separator 21 is effective to deliver a control signal for synchronizing the scanning operation of the receiver which initiates at the leading edge of the second field-synchronizing pulse of curve A, thus to provide accurate timing of the operation of field-scanning circuit 19. It will be understood, however, that field-scanning circuit 19 need not depend entirely for its synchronization upon energy derived from an edge of a synchronizing pulse, because the whole of the energy of the field-synchronizing pulse of curve A following the first pulse is available for synchronizing the field-scanning circuit 19.

Furthermore, it will be understood that tube 44 comprises an arrangement responsive to the sensitizing pulse D and to the composite synchronizing signal for deriving the desired control voltage and that in other embodiments of the invention the composite synchronizing signal can be applied directly to tube 44 rather than being applied through tube 33.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-synchronizing pulses comprising, means including an integrating circuit responsive to a predetermined one of said field-synchronizing pulses of each field-underlap interval and substantially unresponsive to said line-synchronizing pulses

for deriving a sensitizing signal initiating at the trailing edge of said predetermined one of said field-synchronizing pulses, and means responsive jointly to said sensitizing signal and to the field-synchronizing pulse of said composite synchronizing signal for deriving a control signal from the field-synchronizing pulse following said trailing edge.

2. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-synchronizing pulses comprising, means including an integrating circuit responsive to the first of said field-synchronizing pulses of each field-underlap interval and substantially unresponsive to said line-synchronizing pulses for deriving a sensitizing signal initiating at the trailing edge of said first of said field-synchronizing pulses, and means responsive jointly to said sensitizing signal and to the field-synchronizing pulses of said composite synchronizing signal for deriving a control signal from the second field-synchronizing pulse of each field-underlap interval.

3. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-synchronizing pulses comprising, means including an integrating circuit responsive to a predetermined one of said field-synchronizing pulses of each field-underlap interval and substantially unresponsive to said line-synchronizing pulses for deriving a sensitizing signal initiating at the trailing edge of said predetermined one of said field-synchronizing pulses, and means responsive jointly to said sensitizing signal and to the field-synchronizing pulses of said composite synchronizing signal for deriving a control signal initiating at the leading edge of the field-synchronizing pulse following said trailing edge.

4. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-synchronizing pulses comprising, means including an integrating circuit responsive to the field-synchronizing pulses of said composite signal and substantially unresponsive to the line-synchronizing pulses thereof for deriving a first sensitizing signal during each field-underlap interval, means responsive to said first sensitizing signal for deriving a second sensitizing signal initiating at the trailing edge of a predetermined one of said field-synchronizing pulses of each field-underlap interval, and means responsive jointly to said first and second sensitizing signals for deriving a control signal from the field-synchronizing pulse following said trailing edge.

5. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-

synchronizing pulses comprising, means including an integrating circuit responsive to the field-synchronizing pulses of said composite signal and substantially unresponsive to the line-synchronizing pulses thereof for deriving a first sensitizing signal during each field-underlap interval, an energy-storage device including a short time-constant charging circuit and a long time-constant discharging circuit responsive to

5 said first sensitizing signal for deriving a second sensitizing signal initiating at the trailing edge of a predetermined one of said field-synchronizing pulses of each field-underlap interval, and means responsive jointly to said first and second sensitizing signals for deriving a control signal from the field-synchronizing pulse following said trailing edge.

6. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-synchronizing pulses comprising, a resistor-condenser network responsive to the field-synchronizing pulses of said composite signal and substantially unresponsive to the line-synchronizing pulses thereof for deriving a first sensitizing signal during each field-underlap interval, means responsive to said first sensitizing signal for deriving a second sensitizing signal initiating at the trailing edge of a predetermined one of said field-synchronizing pulses of each field-underlap interval, and means jointly responsive to said first and second sensitizing signals for deriving a control signal from the field-synchronizing pulse following said trailing edge.

7. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-synchronizing pulses comprising, means including a resistor connected in series with a parallel-connected resistor and condenser responsive to the field-synchronizing pulses of said composite signal and substantially unresponsive to the line-synchronizing pulses thereof for deriving a first sensitizing signal during each field-underlap interval, means responsive to said first sensitizing signal for deriving a second sensitizing signal initiating at the trailing edge of a predetermined one of said field-synchronizing pulses of each field-underlap interval, and means jointly responsive to said first and second sensitizing signals for deriving a control signal from the field-synchronizing pulse following said trailing edge.

8. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-synchronizing pulses comprising, means for integrating said composite signal to derive a first sensitizing signal during each field-underlap interval, means including a diode connected in series with a parallel-connected resistor and condenser and responsive to said first sensitizing signal for deriving a second sensitizing signal ini-

tiating at the trailing edge of a predetermined one of said field-synchronizing pulses of each field-underlap interval, and means responsive jointly to said first and second sensitizing signals for deriving a control signal from the field-synchronizing pulse following said trailing edge.

9. In a television signal-translating system, a synchronizing-signal separating apparatus adapted to be energized by a composite synchronizing signal including line-synchronizing pulses and a plurality of field-synchronizing pulses for each field-underlap interval of the same polarity as, but having a greater duration than, said line-synchronizing pulses comprising, means for integrating said composite signal to derive a first sensitizing signal during each field-underlap interval, a vacuum tube normally biased to cutoff, means for utilizing said first sensitizing signal for sensitizing said vacuum tube, means coupled to the output circuit of said vacuum tube for deriving a second sensitizing signal initiating at the trailing edge of a predetermined one of said field-synchronizing pulses of each field-underlap interval, and means responsive jointly to said

first and second sensitizing signals for deriving a control signal from the field-synchronizing pulse following said trailing edge.

10. In a television signal-translating system, 5 a synchronizing-signal separating apparatus adapted to be energized by a composite synchronizing signal including line-synchronizing pulses and a plurality of field-synchronizing pulses for each field-underlap interval of the same polarity as, but having a greater duration than, said line- 10 synchronizing pulses comprising, means for integrating said composite signal to derive a first sensitizing signal during each field-underlap interval, quickly-responsive and slowly-recovering means responsive to said first sensitizing signal for deriving a second sensitizing signal initiating at the trailing edge of a predetermined one of said field-synchronizing pulses of each field-underlap interval, and means including a vacuum 15 tube normally biased to cutoff adapted to be sensitized by said first and second sensitizing signals for deriving a control signal from the field-synchronizing pulse following said trailing edge.

JOHN C. WILSON.
